A. Blipham,
Attorney.

UNITED STATES PATENT OFFICE.

WILLIAM C. BAKER, OF AMESBURY, MASSACHUSETTS.

HEADLIGHT-DIMMER.

1,359,656.

Specification of Letters Patent. Patented Nov. 23, 1920.

Application filed December 19, 1919. Serial No. 345,982.

To all whom it may concern:

Be it known that I, WILLIAM C. BAKER, a citizen of the United States, and a resident of Amesbury, in the county of Essex and Commonwealth of Massachusetts, have invented certain new and useful Improvements in Headlight-Dimmers, of which the following is a full, clear, and exact specification.

10 The object of this invention is the construction of improved means for reducing or dimming at will the intensity of illumination of the head lights of automobiles and the like, both for the purpose of saving 15 approaching vehicles or of pedestrians crossing the road ahead from the blinding effects of the glare, and also as a means for signaling to other automobiles or trucks.

To this end I have provided a foot operated push button adapted when depressed to switch into the lighting circuit a sufficient amount of resistance to reduce the intensity of the electric head light the desired extent.

20 In the drawings forming part of this specification, Figure 1 is a central vertical section of a dimmer embodying my improvements, showing the same wired to a head light and a source of current. Fig. 2 is a horizontal section on the line 2—2 in 25 Fig. 1.

30 As shown, the head light 1 is connected by a wire 2 to a source of current 3, while wires 4 and 5 pass respectively from the head light and the current source to the dimmer.

35 The dimmer comprises a stem or bolt 6 having a broad head 7 at its lower end, and a button 9 at its upper end. Normally in contact with the head 7 are two contact 40 blocks 10, 11, one in circuit with the wire 4 and the other with the wire 5.

45 With the head 7 thus in touch with both of the contacts 10 and 11, the current passes from the source 3 through the wire 5 to the contact 10, thence through the head 7 to the contact 11, and the wire 4 to the light 1, then through the wire 2 back to the source.

50 The contacts 10, 11 are supported by an insulating sleeve 12 through which the bolt 6 freely passes, and spaced from these contacts is a coil of insulating wire 13 for which the sleeve 12 acts as an insulating

spool. The terminals of this coil are connected, as by wires 14, 15, to the contacts 10, 11, so that whenever the bolt head 7 is 55 depressed and thereby breaks the circuit between these contacts, the only path for the current is through the wires 14, 15 and the coil 13. The amount of resistance thus introduced into the circuit at once reduces 60 the intensity of current delivered to the head light, and correspondingly reduces the intensity of its illumination.

The bolt 6 is normally held with its head 7 in touch with the contacts 10, 11 by means 65 of a helical spring 16 between a plate 17 which is suitably fastened to the sleeve 12 and to the automobile floor or other suitable place, and the under surface of the button 9 or a washer 18 beneath it, which is preferably screwed onto the bolt 6.

70 Thus constructed, all that needs to be done in order to dim the head light is to press down on the button 9 sufficiently to remove its head 7 out of touch with the 75 contacts 10, 11. If the chauffeur wishes to flash a signal to someone ahead, he can depress the button in a series of dots and dashes or other combinations of alternating 80 light and semi-darkness.

What I claim is:

A head light dimmer comprising a thimble composed of insulating material, the thimble having a contracted portion near its upper end, resistance coils located in said 85 contracted portion, contact terminals attached to the lower portion of said thimble, one contact terminal in circuit with one terminal of said coils and the other with the other terminal of the coils, a plunger 90 located in the axial center of said thimble and freely reciprocative therein, said plunger having a head at its lower end adapted to be in touch with both of said contact terminals when the plunger is in its uppermost 95 position, a knob attached to the upper end of said plunger, and a helical spring between said knob and thimble for normally holding the said head in touch with said contact terminals.

100 In testimony that I claim the foregoing invention, I have hereunto set my hand this 16th day of December, 1919.

WILLIAM C. BAKER,
